(57) **CLAIM**

We claim the ornamental design for a vascular compression device, as shown and described.

DESCRIPTION

FIG. 1 is an isometric view of the vascular compression device.

FIG. 2 is a front elevation of the vascular compression device corresponding to FIG. 1.

FIG. 3 is a right side elevation of the vascular compression device corresponding to FIG. 1, the left side elevation being a mirror image thereof.

FIG. 4 is a rear elevation of the vascular compression device corresponding to FIG. 1.

FIG. 5 is a top plan view of the vascular compression device corresponding to FIG. 1; and,

FIG. 6 is a bottom view of the vascular compression device corresponding to FIG. 1.
